UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

ELECTRIC SWITCH.

Application filed January 2, 1924. Serial No. 684,003.

My invention relates to electric switches, particularly those for controlling high potential currents of large capacity.

For the control of high potential power circuits, switches of the oil break type heretofore have been almost universally employed and as to the development of the art has been accompanied by the use of power circuits of ever increasing voltage, the construction of switches for the satisfactory control of such circuits has presented many difficult problems and has involved great expense. Large capacity oil switches have required the use of large quantities of oil and, because of the generation of great quantities of highly heated gas by the arc within the oil when the switch is opened under a heavy load, the switch contacts and oil have been enclosed in strong steel tanks capable of withstanding the high pressures generated in order to avoid the loss of oil and the risk of fire and personal injury. Not only is the cost of manufacture of such apparatus excessive but because of its size serious transportation difficulties often arise in placing the apparatus after it is manufactured.

It is an object of my present invention to provide a construction of switch for controlling high voltage circuits which shall avoid the above mentioned dangers, shall comprise parts of moderate dimensions facilitating transportation, shall be manufacturable at a relatively low cost and be efficient in operation.

My invention will be better understood by reference to the accompanying specification and drawing and its scope will be pointed out in the appended claims.

In the drawing, Figure 1 is a simple diagrammatic sketch showing the gist of the invention and Fig. 2 is a more complete diagrammatic showing of one manner of carrying out the invention.

Before proceeding with the detailed description, I desire to point out that in illustrating my invention, I have made no attempt to show the various parts in their relative proportions but, in a diagrammatic manner only.

Referring first to Fig. 1 of the drawing where I have shown diagrammatically the more essential features of my invention, the main break in the circuit to be controlled is between contacts 1 and 2 of which the

former is shown as a stationary socket and the latter a downwardly movable rod. The stationary contact 1 is located above an open vessel 3 of comparatively small diameter and of insulation containing a liquid 4 of fairly high dielectric strength through which the movable contact 2 projects and is adapted to be moved vertically into and out of contact with the stationary contact. For moving contact member 2, it is shown provided with a piston head 5 which is adapted to slide in a cylinder 6, the cylinder being connected at a point above the piston by a pipe 7 leading to a pressure device. Pressure for operating the piston is obtained by a preliminary interruption of the circuit at a point other than at the main contacts and in a medium which will be vaporized or disassociated to form a gas or gases. According to Fig. 1 this may be accomplished by providing a switch having a movable contact 9 and a stationary contact 10 mounted on an insulator 11 in the bottom of the closed vessel 12 which is filled with a liquid which will produce a gas when subjected to the action of an arc and which is connected with the cylinder 6 by the pipe 7. This pipe should be of sufficient size to freely transmit pressure to vessel 6. The movable member 9 of the switch is shown attached to the plunger 13 of the series solenoid 14 of which one terminal connects with the line to be controlled while the other terminal connects with stationary contact 10. The movable contact 9 is in electrical connection with the main contact 2, such connection being indicated by a dotted line in Fig. 1. Supposing both sets of contacts to be in closed circuit position and contact 1 to be connected to the line, an overload current of a predetermined value will actuate the solenoid 14 to separate contacts 9 and 10 and draw an arc in the closed vessel 12. The resulting vapor or gas produced being communicated to the cylinder 6 causes a rapid downward movement of the piston 5 and attached contact rod 2. Thus the circuit is opened between contacts 1 and 2 which constitutes the main break and an arc is quickly drawn first through the air alone and finally into the insulating liquid contained in the vessel 3. Because of the small diameter of the vessel 3, the sudden formation of gas therein causes a stream of cool liquid to be thrown directly

into the arc. The break produced by the operation of switch 9 is intended to effect only a partial interruption of the line circuit and while it thus assists in the final 5 interruption of the circuit its principal object is the production of an arc in a liquid which will be vaporized or disassociated for the purpose of generating suitable pressure to actuate the main switch rod 2.

Having thus briefly explained the chief 10 characteristics which constitute the gist of one feature of my invention by means of the diagram comprising Fig. 1 of the drawing, I shall now proceed to describe in greater 15 detail, by the aid of the diagram comprising Fig. 2, apparatus which might be used to carry out my invention.

The switch being adapted for the control 20 of a high potential circuit obviously must be supported in such a manner as to be thoroughly insulated from the ground. The operating mechanism of the switch being actuated as a result of the sudden generation 25 of gas pressure, in the nature of an explosion, the insulating supports will be subjected to severe shocks and vibrations which, as is well known to those skilled in the art, are not adapted to be successfully withstood by rigid insulator supports such for example 30 as porcelain. In Fig. 2 I have shown the entire switch mechanism suspended from an overhead frame work by flexible insulators of the suspension type whereby the shocks and vibrations incident to the operation of 35 the mechanism may be absorbed or dissipated without injury to the insulating means.

A truss 16 is shown resting at its ends on cross channels 17 which in turn are supported 40 on standards 18. Near each end of the truss hangs an insulator string 20 whose lower end carries a cross member 21. Intermediate the ends of the insulator string, a cross member 22 is secured, at one end of 45 which a connection is made to the line as at 23 and at the midpoint of which the covered stationary contact is attached. This contact may be of any suitable form to frictionally engage the rod 2 as for example the contact 50 shown in the patent to E. W. Rice #812,880. Suspended from the member 21 is the cylindrical metal vessel 6, secured into the top of which is the small vessel 3 of insulating material. The piston 5 fits the vessel 6 and has 55 secured to it the contact rod 2 which extends up through the vessel 3 to engage the stationary contact 1. Contacts 25 attached to a partition 26 in vessel 6 serve to provide a good electrical connection between that 60 member and the contact rod 2. The vessel 6 is closed at its lower end by a cap 27 and near that end is provided with a series of longitudinal slots 28. In the region of the slots 28, the vessel 6 is shown surrounded 65 by a second casing 29 of larger diameter

forming therewith a closed receptacle which communicates through a plurality of pipes, diagrammatically illustrated by a single pipe 30, with a reservoir 31 situated on the cross bar 21. The vessels, the pipe and the 70 reservoir thus far described may be filled to the level indicated with a suitable liquid such for example as water, a mixture of water and glycerine or other liquid having a fairly high dielectric strength. With the 75 piston and rod in the position illustrated it will be readily apparent if pressure is admitted to the vessel 6 below the partition therein the piston and rod will be forced down thereby breaking connection with the 80 stationary contact 1 and coming to rest slowly as the piston approaches the lower ends of the slots 28 when the flow of liquid to the reservoir 31 becomes more and more restricted. As has been explained above the 85 necessary pressure for operating the piston 5 is produced by the gas generated by the 90 arc formed at an auxiliary switch 11. This switch and the closed vessel 12, in which it is located, is shown supported from the cross member 21 and connected with the vessel 6 by pipe 7. A vent tube 33 permits the slow escape of gas from the vessel 12 to the atmosphere and a small tube 34 leads to a reservoir 35, the same liquid being used 95 in the closed vessel 12 and reservoir 35 as in the vessels 6 and 3. The switch 9 is electrically connected with the chamber 12 through brushes 37 while the stationary 100 operating contact 10 is insulated therefrom by insulator bushing 11. The contact 9 is connected to core 13 and adapted to be moved to open circuit position by the solenoid 14. The solenoid 14 is shown normally shunted by a switch 38 which is adapted 105 to be opened by a solenoid 39 whenever the current in the line reaches a predetermined value. The line to be controlled may be connected by lead 23 to the cross member 22 and from the solenoid 14, a wire 40 may lead 110 to a disconnecting switch shown diagrammatically at 41 and from thence to the line by wire 42. The contact rod 2 is held frictionally in its upper or circuit closing position and in order that it may be returned to that position after having been actuated to open the line circuit, suitable means, as for example, a rod 44 may be provided which passes up through a stuffing box 45 in the 115 cover 27. Rod 44 has an insulation section 46 therein and a handle 47 at its lower end. To enable the main switch to be opened manually, the piston 5 is shown carrying a collar 49 having a bayonet slot therein in which a small cross rod 50 at the upper end 120 of rod 44 is adapted to engage.

Although I have shown and described apparatus for interrupting the circuit through a single conductor or phase it will be understood that I contemplate providing 130

duplicate apparatus to be suspended from a truss similar to that shown at 21 and supported in parallel relation therewith for the control of a metallic circuit single phase 5 transmission line. Likewise for the control of a three phase line I may use the same apparatus in triplicate. In either case the standards or towers 23 would be suitably positioned so as not to interfere with the 10 mechanism.

The operation of the more complete mechanism which I have illustrated by way of example in Fig. 2 is as follows: Assuming the parts to be in the relative positions 15 shown by the drawing, the line current may be considered to enter at the connection 23, pass through the member 22 to contact 1, to rod 2, through contacts 25 to member 6 through supporting member 21 and pipe 7 20 to vessel 12 to switch rod 9. From the stationary switch contact 11 it passes to the solenoid 39, through switch 38 to wire 40 to disconnecting switch 41 to the line by wire 42. Normal values of line current are in- 25 sufficient to operate the solenoid 39 but upon the occurrence of a predetermined overload the solenoid 39 will open the switch 38 there- 30 by causing the operation of solenoid 14 and an opening of the switch 9. The arc drawn by the opening of this switch suddenly gen- 35 erates a considerable quantity of gas in the chamber 12 and since the vent tube 33 and the reservoir tube 34 provide only restricted outlets for the escape of gas and liquid the resulting pressure in the chamber 12 is re- 40 lieved principally by the pipe 7 leading to the vessel 6. Piston 5 is immediately forced down, the rod 2 breaking connection with contact 1 and opening the main circuit. The 45 arc of the main break is thus drawn first through air and then as the end of the rod 2 becomes submerged upon continued downward movement, the arc is also drawn through the liquid in the cylinder 3. As the piston moves downwardly the liquid be- 50 neath it is forced out through the slots 28, through pipe 30 into reservoir 31. After the piston reaches the upper ends of the slots 28 the escape of liquid becomes more and more restricted until, and when the piston reaches its lower limit, the slots 28 are en- 55 tirely closed. A gradual checking of the movement of the piston and contact rod is thereby effected. After the main circuit has 60 been broken as described above the disconnect switch may be opened. It will be noted that the switch 9 in the chamber 12 is free to close by gravity when the line circuit is finally opened.

60 The main contact rod 2 may be raised to closed circuit position by pushing up on the rod 44, the rod 2 being frictionally held in closed circuit position. Likewise the rod 2 may be lowered by hand to open the switch 65 manually by first raising the rod 44 and

rotating it to engage the bayonet slots in the collar 49 and then pulling down.

I do not wish to be limited to the particular arrangement and construction shown and described herein as it will be apparent to 70 those skilled in the art that many modifications therein may be made without departing from the scope of my invention as set forth in the appended claims.

What I claim as new and desire to se- 75 cure by Letters Patent of the United States, is:—

1. A high potential switch comprising an elevated supporting structure, stationary and movable cooperating contacts, fluid 80 pressure actuated operating means therefor, flexible insulating means connected at its lower end with the movable contact and the operating means for freely suspending the same from said structure and means secured 85 to the flexible insulating means at a point intermediate its ends for supporting the stationary contact.

2. A high potential switch comprising a stationary contact, a vessel containing in- 90 sulating liquid below said stationary contact, a movable contact adapted to extend up through said liquid to engage said stationary contact, means for drawing an arc in an insulating fluid, to produce a fluid 95 pressure, and means actuated by said fluid pressure for withdrawing said movable contact from said stationary contact to a position below the level of said liquid.

3. A high potential switch mechanism 100 comprising a main switch, an auxiliary switch having contacts separable in a liquid convertible into gas by the arc formed upon the separation of its contacts, and means whereby the gas pressure produced by the 105 opening of said auxiliary switch moves the main switch to open circuit position.

4. An electric switch comprising a sta- 110 tionary contact, a narrow open receptacle spaced below the stationary contact and containing insulating liquid, a contact rod mounted centrally in said receptacle and movable through the bottom thereof, and means for quickly withdrawing the contact rod from the stationary contact, through the 115 intervening space to a position below the surface of the liquid in the receptacle.

5. An electric switch mechanism comprising a pair of relatively movable contacts, a closed vessel containing a liquid, a second 120 pair of relatively movable contacts in said liquid adapted to draw an arc when separated and means responsive to the pressure in said vessel produced by said arc for separating said first contacts. 125

6. An electric switch mechanism comprising a pair of relatively movable contacts, pressure actuated means for separating said contacts, a closed vessel containing liquid, a second pair of contacts immersed in said 130

liquid adapted when opened to draw an arc in the liquid and create a pressure in the vessel, and means for communicating said pressure to said pressure actuated means.

5. An electric switch mechanism comprising a stationary contact, a narrow open vessel containing insulating liquid spaced beneath said contact, a cooperating movable contact rod mounted to extend up centrally

through the liquid in said vessel, a fluid pressure operated member on said rod adapted to withdraw the rod from the stationary contact to a position beneath the surface of the liquid and load responsive means for subjecting said member to fluid pressure. 10

In witness whereof, I have hereunto set my hand this 31st day of December, 1923.

JOHN D. HILLIARD. 15
